UNITED STATES PATENT OFFICE.

JOHN S. HAAS AND RICHARD BERNHARD, OF ALLEN TOWN, PENNSYLVANIA, ASSIGNEES TO TRAYLOR ENGINEERING & MANUFACTURING COMPANY, OF ALLEN TOWN, PENNSYLVANIA, A CORPORATION OF DELAWARE.

GYRATORY CRUSHER.

Application filed January 12, 1924. Serial No. 685,763.

Our invention relates to gyratory crushers, and especially to the exclusion of dust, grit, or the like from their working parts, bearing, lubricating systems, etc. We aim to provide 5 novel means of protection for this purpose, that may be variously adapted and applied to keep dust or the like from entering between gyratory parts and parts that are "fixed" in the sense of not gyrating,—whether truly 10 stationary, rotary, or shiftable in an axial direction. Such locations include, for example (to cite only a few illustrative types of crusher construction), joints between the gyratory member on the one hand and the rotat- 15 ing eccentric and its driving gear on the other hand, (U. S. Patent No. 463,539 to McCully); or between the gyratory member and the eccentric bearing, (U. S. Patent No. 431,069 to Lowry); or between the gyratory member 20 and a housing on a diaphragm sloping down over the whole driving mechanism of the crusher, and affording a "chute" for discharging crushed material. (U. S. Patent No. 535,716 to McLanahan.). In suitable and 25 preferred embodiments (such as that herein-after described), the invention obviates serious defects of dust-excluding means heretofore employed.

The drawing shows a vertical section 30 through one type of gyratory crusher equipped with a dust-excluding device or seal conveniently embodying our invention,—the upper part of the crusher structure being broken away and omitted.

A conventional form of gyratory crusher 35 is illustrated, with casing 10 mounted on base 11, and with gyratory member comprising crusher shaft 14 (fulcrumed and suspended for vertical adjustment in any suitable man- 40 ner, not shown), and its head 15. The base 11 has a central bearing hub 16 for the revolving eccentric 17 that actuates the lower end of the shaft 14 to produce the gyratory crushing motion of the head 15. The shaft 14 45 does not rotate with the eccentric 17, but merely "wobbles" as the latter revolves. The bearing 16 is provided with a renewable lining 18, and the lower end of the shaft 14 is equipped with a sleeve 19 for accommodating 50 its vertical adjustment and gyratory "wobble", loosely keyed to the shaft at 19^a and working in the bore of the eccentric 17. The eccentric 17 is driven by connections and mechanism including a horizontal counter-

shaft 20 in a bearing 20^a in the base 11, a bevel pinion 21 on the inner end of the shaft 20, and a cooperating bevel gear 22 fast to the lower end of the eccentric.

In the operation of this (or any other gyratory type of crusher), the crushed material falls from the narrow opening between the head 15 and the casing 10, on its way to discharge, so that large quantities of dust are always present in this region, ready to enter any openings between fixed and gyratory parts and find their way to any bearings or other operating parts thus accessible. Heretofore, it has been attempted to prevent this by means of an annular sealing member around the crusher shaft, resting on and sealing horizontally with a subjacent fixed part to accommodate the gyratory motion, and sealing vertically with the gyratory member to accommodate vertical movement or shifting,—as for adjustment of the crusher head 75 to vary the size of the crushed product. Such constructions, however, have been subject to serious drawbacks: e. g., through rust or the cementing action of the crushed material (or both combined), the sealing ring would 80 "freeze" to the gyratory member, and thus be lifted and held off its seat when the gyratory member was subsequently raised for purposes of adjustment; the sealing ring would become jammed to the gyratory member in a "cocked" 85 position, and thus at once rendered ineffectual; accumulation of damp stone dust would eventually lift the ring off its seat and enter beneath it, through wear, the tightness of the vertical seal would become impaired, without 90 possibility of restoration by any practicable adjustment or replacement of parts.

In the embodiment of our invention here illustrated, there is an annular dust-excluding member 24 movably engaged and sealed with the gyratory member (in this case at the lower portion of the crushing head 15) to take care of gyratory movement, and movably engaged and sealed with a stationary, fixed part, to permit vertical adjustment. For this purpose, the member 24 rests and seals horizontally on an annular ledge 25 at the bottom of the crushing head 15, and seals circumferentially, with a journal fit, on the cylindrical upper portion of a fixed stationary dust-excluding housing 26 that encloses the upper ends of eccentric 17 and shaft sleeve 19. In the present instance, the lower portion of the

crushing head is outside the annular member 24, and the housing 26 extends up inside of it. In order to maximize the shelter of the joint by the head 15 naturally resulting from this 5 relation of the parts, the upper cylindrical portion of the housing 26 is made as small as consistent with affording safe clearance for the gyration of the shaft 14 inside it. The lower portion of this housing 26, on the other 10 hand, is flared out and provided with a horizontal flange 27 for fitting snug against the upper end of the hub 16 to exclude dust. The housing 26 is bolted at 28 to one of the non-gyrating or fixed parts, such as the hub 16. It 15 has a depending shoulder 29 adapted to engage around the eccentric 17 and inside the hub 16 above its lining 18, and thus aid in the accurate alignment of the parts.

In the present instance, the reentrant con- 20 formation at the bottom of the crusher head 15 naturally required by the arrangement of the parts 24, 25, 26, described above is afforded partly by recessing the main head piece itself, and partly by a separate annular dust- 25 excluding member 30, whose inner flange-like portion constitutes the sealing ledge 25 already mentioned. This member 30 is bolted fast to the bottom of the head piece 15, with an upstanding shoulder 31 engaged in a rab- 30 beted seat in the head to assure accurate alignment. In the present instance, the mem- 35 ber 24 not only seats and seals on the ledge 25 at its lower side, but also at its upper side, against an annular shoulder 32 on the main head piece 15. Thus the member 24 is in effect engaged in an internal groove in the bottom portion of the head 15. Preferably, the member 24 fits this groove with a snug working fit, so as to assure dust-tightness 40 without binding or undue friction.

As shown, upper and lower surfaces of the member 24 and the seating surface of the ledge 25 are spherical, and struck from a common center in the axis of the shaft 14, 45 preferably corresponding to the center of suspension and gyration of the shaft; this minimizes wear, gives utmost efficiency of dust-exclusion, and obviates any tendency for the gyratory movement to tilt or "cock" the member 24 on the housing 26,—thus allowing 50 the snuggest possible sliding fit of these latter parts to be employed and maintained over an ample width. The seating surface of the shoulder 32 may preferably be likewise spherical, and concentric with the gyration of the shaft 14.

From the foregoing description, it will be seen that contact over ample area is always afforded at all the sealing surfaces, notwithstanding the gyratory motion of the parts 60 or their vertical movement. Not only are the dust excluding member 24 and all its sealing contacts most effectively sheltered under the head 15 and by the member 30,—without 65 variation in this respect by vertical adjust-

ment,—but the member 24 is at all times definitely and positively kept sealed with the gyratory member by virtue of its engagement between the portions 25 and 32 of the latter, each of which holds it sealed with the other as 70 against packed material under it, tightness on the part 26, or any other influence tending to unseat it. The advantages of this feature are, of course, not dependent on the member 24 being associated with a gyrating part 75 for relative movement horizontally, as in the present instance.

The metal parts 24, 26, 30 involved in the seal are all relatively simple and inexpensive to manufacture, install, or replace, so that 80 wear can readily be compensated for by such replacement. Lateral wear of the sealing ring 24—and even wear of the head shoulder 32—can easily be compensated by cutting a thin layer of metal off the upper side of the 85 member 30, without necessity for any replacement whatever.

Besides closing the space between the dust excluding member 24 and the top of the eccentric hub 16, and preventing gyration of the 90 member 24, the protective housing 26 affords an annular chamber 34 for receiving oil raised to the upper part of the eccentric 17 (by any suitable means, not shown) from a subjacent reservoir 35, through the interior of the 95 eccentric, around the shaft sleeve 19. After lubricating the bearing surfaces of the parts 17 and 19 on its way to the chamber 34, this oil may be delivered and distributed from the latter to any other surfaces requiring lubrication: e. g., through grooves in the hub lining 18 around the eccentric 17, and to the counter-shaft bearing 20^a via a passage 36 in the hub and a pipe 37 discharging into a cup on the exterior of the bearing,—into the 100 interior of which it may make its way through holes 20^b in the latter, as usual in such cases. Ultimately, the oil may all return by gravity to the reservoir 35, for recirculation.

In connection with such a circulatory lubricating system, the security of the sealing means described above is especially valuable; because the circulation through the chamber 34 makes it well-nigh inevitable that any dirt 115 entering this chamber will find its way into the bearings and injure them,—if, indeed, it does not block the oil circulation altogether, or otherwise cause a burned bearing and a costly shut-down of the crusher.

Having thus described our invention, we claim:

1. A seal for a gyratory crusher comprising a member engaging and sealing horizontally with a gyrating part, for movement relative thereto, and also sealed with a fixed part of the crusher for vertical movement relative thereto.

2. A seal for a gyratory crusher comprising a member engaging and sealing vertically

- with a fixed part of the crusher, for movement relative thereto, and also sealed with a gyratory part for movement relative thereto.
3. A seal for a gyratory crusher comprising a member engaging and sealing horizontally with a gyrating part, and adjustable vertically therewith, and also engaging and sealing vertically with a fixed part, to permit such adjustment.
- 10 4. A seal for a gyratory crusher comprising a member engaging and sealing horizontally with one of the gyrating parts of the crusher, for movement relative thereto, and means on said gyratory part for holding said member sealed therewith.
- 20 5. A seal for a gyratory crusher comprising a member engaging and sealing circumferentially with one of the relatively gyrating parts of the crusher, for vertical movement relative thereto and engaging and sealing horizontally with another such part, for gyratory movement relative thereto, and means for holding said member sealed with said latter part.
- 25 6. A seal for a gyratory crusher comprising a member engaging and sealing circumferentially around a fixed part of the crusher, for vertical movement relative thereto.
- 30 7. A seal for a gyratory crusher comprising a member sealing circumferentially with a fixed part surrounding the gyratory crusher shaft, for vertical adjustment relative to said part.
- 35 8. A seal for a gyratory crusher comprising a member engaging and sealing circumferentially with a fixed part of the crusher, for movement relative thereto, and engaging and sealing horizontally with the gyratory crushing head, for movement relative to the latter.
- 40 9. A seal for a gyratory crusher comprising a dust excluding member supported by the gyratory crushing head and sealed therewith for movement relative thereto.
- 45 10. A seal for a gyratory crusher comprising a member engaging and sealing around a fixed part of the crusher for movement relative thereto, and also engaging and sealing within the gyratory crushing head, for movement relative to the latter, with means on the head for holding said member sealed therewith as aforesaid.
- 50 11. In a seal for a gyratory crusher, the combination of a crusher head having an annular supporting ledge at its lower end, and an annular dust excluding member resting on and sealing with said ledge.
- 55 12. In a seal for a gyratory crusher, the combination of the crusher head, a supporting ring detachably secured to the bottom of the head and affording an internal ledge beneath the head, and an annular dust excluding member resting on said ledge and sealing therewith.
- 60 13. In a seal for a gyratory crusher, the combination of a crusher head having an annular groove at its lower end, and an annular dust excluding member movably engaged in said groove and laterally sealing with its sides.
- 70 14. In a seal for a gyratory crusher, the combination of a crusher head having at its lower end an internal annular groove with spherically-surfaced sides, and an annular dust excluding member with correspondingly spherically-surfaced sides engaged between the sides of said groove in sealing contact therewith.
- 75 15. A seal for a gyratory crusher comprising a member supported by the gyratory crushing head and sealed therewith for movement relative thereto, and also sealed with a fixed part of the crusher structure for adjustment relative thereto.
- 80 16. A seal for a gyratory crusher comprising, in combination with the eccentric hub of the crusher and the gyratory crusher head, an annular dust excluding member supported by the head, and a protective housing mounted on the eccentric hub closing the space between said hub and said dust excluding member, and also preventing gyratory movement of the latter.
- 85 17. A seal for a gyratory crusher, comprising a dust excluding member carried by the gyratory crushing head and a rigid ring sealed therewith for relative movement between the two, and said ring sealed at its inner circumference around a fixed part of the crusher structure.
- 90 18. In a seal for a gyratory crusher, the combination of the crushing head, and a circumferential bearing ring secured to the bottom of the head affording a bearing surface beneath the head, and an annular dust excluding member bearing against said ring and sealing therewith, and an extension of the eccentric hub within said dust excluding member cooperating therewith to exclude dust.
- 95 19. In a seal for a gyratory crusher, the combination of a crusher head having an annular ring at its lower end, and an annular dust excluding member movably engaged with said ring and sealing therewith and also with a fixed part of the crusher structure radially within said dust excluding member.
- 100 20. A seal for a gyratory crusher, comprising in combination with the eccentric hub of the crusher and the gyratory crusher head, an annular dust excluding member carried by the head, and a protective housing mounted on the eccentric hub, and a dust ring in contact with the outside of said housing and closing the space between said hub and said dust excluding member, and also sealed in the radial direction with the eccentric hub.
- 105 21. A seal for a gyratory crusher comprising, in combination with the eccentric hub of the crusher and the gyratory crusher head, an

annular dust excluding member movably engaged with the head, and a protective housing mounted on the eccentric hub and movably engaged and cooperating with said member to exclude dust.

22. In a gyratory crusher, a gyrating member and a fixed member, one of said members affording a circumferential sealing groove,

and a sealing element sealing horizontally above and below against the opposite surfaces of said groove.

In testimony whereof, we have hereunto signed our names at Allentown, Pennsylvania, this fourth day of January, 1924.

JOHN S. HAAS.
RICHARD BERNHARD.
